[57] CLAIM

The ornamental design for a film cutting apparatus, substantially as shown and described.

DESCRIPTION

FIG. 1 is a top and left front perspective view of a film cutting apparatus showing my new design;

FIG. 2 is a top and left rear perspective view thereof;

FIG. 3 is a left side elevational view thereof, the right side being substantially similar thereto;

FIG. 4 is a bottom plan view thereof.

FIG-1-

FIG-2-

FIG-3-

FIG-4-
